UNITED STATES PATENT OFFICE.

CHARLES McDougall, of Allentown, Pennsylvania.

NUT LOCK.

Application filed March 7, 1927. Serial No. 173,336.

My invention relates to new and useful improvements in nut locks and has for its primary object the provision of an unique self-locking nut and improved means to release the nut when necessary or desirable.

Another object of the invention is to construct a nut lock including a bolt having a longitudinal ratchet groove providing a ratchet for coaction with a plurality of spring actuated pawls distributed about a nut and housed in slots communicating with the bore of said nut, the pawls and their associated springs being protected by a cap, cover or shield removably mounted on the nut.

15 A further object of this invention is to so construct the pawls as to hold them against longitudinal movement in one direction and therefore assist in preventing accidental displacement thereof.

20 A still further object of my invention is to provide for lubricating the working parts of the device.

With these ends in view, this invention consists in the details of construction and combination of elements hereinafter set forth and then specifically designated by the claims.

In order that those skilled in the art to which this invention appertains, may understand how to make and use the same, I will describe its construction in detail, referring by numerals to the accompanying drawings, forming a part of this application, in which:

Figure 1, is a side elevation of the nut lock constructed in accordance with my invention.

35 Figure 2, is a section on the line 2—2 of Figure 1.

Figure 3 is a section on the line 3—3 of Figure 2.

Figure 4, is an edge view of one of the 40 springs.

Figure 5, is a face view thereof.

Figure 6, is a face view of one of the pawls.

Figure 7, is an edge view of the same.

Figure 8, is an end view of the bolt.

45 Figure 9, is a side elevation of the bolt.

Figure 10, is a plan view of the nut with the pawls and springs removed.

Figure 11, is a side elevation of said nut.

Figure 12, is a plan view of the cap, cover 50 or shield.

In carrying out my invention as herein embodied, 15 represents a bolt having two longitudinal grooves 16, formed in the threaded portion thereof, one of the walls of each 55 groove being radial to produce a ratchet 17 while the other wall is curved and gradually

merges into the circumference of the bolt body or shank.

A nut 18 of desirable or suitable configuration is threaded upon the bolt 15 and has radial slots 19 longitudinally thereof and extending from or in communication with the threaded bore 20 of the nut. The slots 19 preferably run the entire height of the nut, but it will be obvious that they might be of less length and the depth of said slots is governed by the size of the parts used therein allowing for movement of said parts.

In the slots 19 are slidably mounted pawls 21 normally forced outward by the flat low 70 springs 22 also within the slots and the upper ends of said pawls are provided with fingers 23 which rest on shoulders formed by outwardly extending angular continuations of the slot 19 and prevent accidental displacement on one direction.

To obviate the chance of displacement in the opposite direction and therefore hold the pawls in place a cap, cover or shield 24 is mounted on the nut so as to cover the outer 80 ends of the slots. This cap has a hole for registration with the bolt and is provided with bendable tongues 25 in spaced relation about its periphery for forcement into the undercut holes 26 distributed about the outer 85 face of the nut.

In order to remove the pawls to permit removal of the nut from the bolt, recesses 27 are formed in the outer face of the nut in the region of the slots so that said recesses cross 90 the outer ends of said slots, then by inserting the nose of a pair of pliers in any recess the desired pawl may be gripped and withdrawn lengthwise from its slot.

Radial oil holes 28 are produced in the nut 95 so as to form communications with the slots 19 whereby the springs and pawls may be lubricated when desired and since it is preferred that said oil holes be formed in the corners of the nut said corners may be notched 100 as at 29.

In practice the nut is first run upon the bolt a short distance and the pawls with their associated springs inserted in the slots 19 after which the cap 24 is fixed in place. The nut may now be screwed home and during the operation the pawls will successively pass the ratchets 17 until the desired adjustment of the nut is obtained, but any retrograde movement will be prevented and therefore the 110 nut can not become accidentally loosened.

Should it be necessary or desirable to re-

move the nut from the bolt, the cap 24 is disconnected from the nut and the pawls withdrawn by pliers or other suitable tool.

Of course, I do not wish to be limited to the exact details of construction herein shown and described as they may be varied within the limits of the appended claims without departing from the spirit of my invention.

Having thus fully described my invention what I claim as new and useful is:

1. A nut lock comprising a bolt having longitudinal ratchets, a nut threaded on said bolt and having a plurality of radial slots communicating with the bore of said nut, the slots having angular continuations at their outer ends, said nut further having recesses formed in the outer face thereof in the region of the slots, pawls slidably mounted in the slots with their upper ends projecting into the recesses to permit access to said upper ends of the pawls, fingers on the upper ends of the pawls extending into the angular continuations of the slots, springs also mounted in said slots to normally force the pawls inwardly, a cap mounted on the outer face of the nut to enclose the pawls and bearing on the pawl fingers to assist in guiding the pawls, said cap having a hole concentric with the bore of

said nut, tongues projecting from the cap and bendable for insertion in undercut holes in the outer face of the nut.

2. The structure set forth in claim 1, wherein the nut has oil holes formed therein communicating with the slots and with notches in the outer surface of said nut.

3. A device of the kind described comprising a bolt having longitudinal ratchets, a nut threaded on said bolt and having a plurality of radial slots communicating with the bore of said nut, the slots having angular continuations at their outer ends, said nut further having recesses formed in the outer face thereof in the region of the slots, pawls slidably mounted in the slots with their upper ends projecting into the recesses to permit access to said upper ends of the pawls, fingers on the pawls extending into the angular continuations of the slots, springs mounted in said slots to normally force the pawls inwardly, and means detachably mounted on the nut and bearing on the pawl fingers to prevent accidental displacement of and assist in guiding the pawls.

In testimony whereof, I have hereunto affixed my signature.

CHAS. McDougall
